(57) CLAIM

The ornamental design for a cartridge for nebulizer, as shown and described.

DESCRIPTION

FIG. 1 is a front perspective view of a cartridge for nebulizer showing my new design;

FIG. 2 is a back perspective view thereof;

FIG. 3 is a top plan view thereof;

FIG. 4 is a bottom plan view thereof;

FIG. 5 is a right-side elevation view thereof;

FIG. 6 is a left-side elevation view thereof;

FIG. 7 is a front elevation view thereof; and,

FIG. 8 is a back elevation thereof, showing the cartridge for nebulizer.

The broken lines are for the purpose of illustrating the unclaimed portions of the article and form no part of the claimed design.
